Primary Examiner — Karen S Acker

Assistant Examiner — Steven B Reinholdt, Jr.

(74) Attorney, Agent, or Firm — Ward and Smith, P.A.;
 Ryan K. Simmons(57) **CLAIM**

The ornamental design for a food container lid having a passthrough utensil recess, as shown.

DESCRIPTION

FIG. 1 is a perspective view of a food container lid having a passthrough utensil recess showing my new design;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.

1 Claim, 5 Drawing Sheets---
